UNITED STATES PATENT OFFICE.

JOHN SCHEIDEMAN, OF WASHINGTON, DISTRICT OF COLUMBIA.

AMMONIA-PURIFIER FOR REFRIGERATING PLANTS.

SPECIFICATION forming part of Letters Patent No. 704,382, dated July 8, 1902.

Application filed March 14, 1902. Serial No. 98,194. (No model.)

To all whom it may concern:

Be it known that I, JOHN SCHEIDEMAN, a citizen of the United States, residing at Washington, in the District of Columbia, have invented certain new and useful Improvements in Ammonia - Purifiers for Refrigerating Plants; and I do hereby declare the following to be a full, clear, and exact description of the invention, such as will enable others skilled in the art to which it appertains to make and use the same.

My invention relates to compression refrigerating or ice plants in which ammonia is used as the freezing agent, has for its object the purification of the ammonia in circulation, and consists in certain improvements which will be fully disclosed in the following specification and claims.

In the accompanying drawings, which form part of this specification, Figure 1 represents a vertical transverse section, partly in side elevation, of my invention; Fig. 2, a side elevation of the liquid-distributing diaphragm detached, and Fig. 3 a top plan view of the same.

Reference being had to the drawings and the numerals thereon, 1 indicates an ammonia-receptacle preferably cylindrical in form, and may be made of a tube with a separable cast-iron bottom 2, secured thereto by screw-threads and soldered at 3; but it is obvious that the bottom may be formed integral with the body of the receptacle. The receptacle is provided with an annular flange 4, a groove 5, a packing-gasket 6, and a separate head 7, having an annular lip 8, which extends into the groove 5, and the head is secured to the flange 4 by bolts 9.

To the inner surface of the head 7 is attached a pipe 10, and to the inner end of said pipe is secured a horizontal liquid-distributing diaphragm 11, which separates the receptacle 1 into a liquid chamber or compartment 12 below the diaphragm and a gas chamber or compartment 13 above the diaphragm. The diaphragm is provided with radial passages 14, which connect with the pipe 10 and lead to the periphery of the diaphragm to distribute the liquid ammonia in thin streams, and the liquid is discharged into a peripheral groove 15 in the edge of the diaphragm, from which the liquid falls in a thin annular sheet-

like body or in fine streams over the ledge 16, and from which body or stream the gas is readily liberated in its descent as it is evolved by heat applied to the exterior of the receptacle 1 around the liquid-chamber 12, and that portion of the liquid ammonia which has not been converted into gas in its descent is subsequently converted by the heat applied.

The gas rising from the liquid ammonia in chamber 12 passes through tubes 17 in the diaphragm into chamber 13, the tubes preventing scale or other solid impurities passing with the gas to a very great extent, and the solid impurities which do pass into the gas-chamber gravitate to the bottom thereof and lie upon the upper surface of the diaphragm, while the free solid impurities rising with the gas in chamber 12 adhere to the lower surface of said diaphragm.

Liquid ammonia or other refrigerant preferably taken from the lowest point of the receiver of a refrigerating plant receives its initial vaporization in its passage through an expansion-valve 18, having a side passage 19 for connecting with the receiver, and the gas set free by the expansion-valve and the liquid ammonia travel through passage 20 in the head 7, pipe 10, and are discharged through the diaphragm 11 and fall into chamber 12, from which the gas liberated from the liquid refrigerant rises through the tubes 17, and the impurities contained in the refrigerant are collected in chamber 12 and discharged therefrom through pipe 21, branch 22, and blow-off cock 23, the upper end of pipe 21 being covered by a cap 24 and is supported by a brace 25, connected to one of the bolts 9.

26 is a tank forming a hot-water jacket which surrounds the chamber 12, and pipe 21 is provided with a steam or hot-water supply pipe 27, connecting with vertical pipe 28 for heating water or supplying hot water to the tank to from 120° to 125° Fahrenheit for converting the liquid ammonia into gas, which gas is discharged from chamber 13 through pipe 29, which connects with a suction-pump, (not shown,) and surplus water in tank 26 overflows through pipe 30. The receptacle 1 is supported in the tank 26 on legs 31, and the tank 26 is supported on legs 32, and the water is drawn off from tank 26 through cock 33 and pipe 34.

The liquid ammonia collected in chamber 12 contains among its impurities oil, weak liquor, scale from the pipes, and other contaminating matter, which weak liquor and oil frequently saponifies in the pipes or coils of the system; but by freeing the anhydrous ammonia of its impurities this saponification is prevented and the plant operated with better results under low pressure and freer from 10 foul gases than under the prevailing systems of operation.

The impurities which collect in chamber 12 are allowed to accumulate in the bottom thereof and are blown off periodically, as required.

Having thus fully described my invention, what I claim is—

1. The combination of an expansion-valve for effecting initial vaporization, and an ammonia-purifier provided with a diaphragm separating the purifier into a liquid-chamber and a gas-chamber, said diaphragm being constructed to distribute the liquid ammonia in the liquid-chamber, means for heating the liquid-chamber, means for conducting gas from the liquid-chamber to the gas-chamber, a discharge-pipe for the gas-chamber, and means for removing the impurities from the liquid-chamber.
2. An ammonia-purifier consisting of a receptacle provided with means for attachment to a liquid-ammonia receiver of a refrigerating plant, a diaphragm permanently separating

ing the receptacle into a liquid and a gas chamber and provided with means for distributing the liquid ammonia, means of communication between said chambers, a connection with the gas-chamber leading to a suction-pump, a discharge for impurities from the liquid-chamber, and means for warming the liquid-chamber.

3. An ammonia-purifier for refrigerating plants, consisting of a receptacle permanently separated into a liquid-chamber and a gas-chamber by a diaphragm having means for distributing liquid ammonia and means of communication between said chambers, a suitable discharge for each chamber, and means for warming the liquid-chamber.

4. An ammonia-purifier for refrigerating plants, consisting of a receptacle having a liquid-supply, a diaphragm having radial passages and a peripheral discharge for distributing liquid ammonia and separate passages for gas extending through said diaphragm, a liquid-chamber below the diaphragm provided with a discharge for impurities, a gas-chamber above the diaphragm provided with means of attachment with a suction-pump, and means for warming the liquid-chamber.

In testimony whereof I affix my signature in presence of two witnesses.

JOHN SCHEIDEMAN.
